UNITED STATES PATENT OFFICE

ROYAL N. RIBLET, OF SPOKANE, WASHINGTON

CONVEYER BUCKET

Application filed March 24, 1931. Serial No. 524,885.

My present invention relates to improvements in conveyer buckets of the invertible dumping type, and particularly to the latch device, or fastening means for retaining the bucket in carrying position.

In carrying out my invention the bucket is provided with a pivoted bail, and the latter is in turn pivotally supported from a hanger frame that is suspended from a carriage or carriages adapted to run or travel on an overhead track or rail. The bail is located off-center with relation to the bucket in order that the latter may readily be inverted for dumping its load at the proper time, and a combined trip-lever and latch is utilized for retaining the loaded bucket in locked or latched position, the trip-lever being adapted to co-act with a stationary trip device for releasing the latch, and tilting the bucket in its bail, for dumping the contents of the bucket.

In the exemplification of the invention herein disclosed, two tandem trolleys or wheel carriages are shown traveling over an overhead rail and drawn by a traction cable. The bail of the conveyer bucket is pivotally supported on an axis arranged transversely of a hanger frame, and the latter is swiveled in or pivotally connected to the two trolleys or carriages.

The invention consists in certain novel combinations and arrangements of parts involving the bail and its pivoted bucket as will hereinafter be more fully set forth and claimed. In the accompanying drawings I have illustrated one complete example of the physical embodiment of my invention wherein the parts are combined and arranged according to the best mode I have thus far devised for the practical application of the principles of my invention.

Figure 1 is a view in side elevation showing the bucket as part of the equipment of an overhead conveyer line, the bucket being carried in latched or loaded position.

Figure 2 is an end view as seen from the right end of Figure 1.

Figure 3 is a view similar to Figure 1, but seen from the opposite side of the conveyer line, and showing the conveyer traveling over an inclined track or rail.

Figure 4 is an enlarged detail section showing the pivot connection for the bail, as at line 4-4 of Figure 2, and Figure 5 is a top view of the parts in Figure 4.

Figure 6 is a view in elevation at the latch end of the bucket, showing part of the bucket, and with the latch device closed.

Figure 7 is a view as seen from the right in Figure 6.

Figure 8 is an enlarged detail view of the latch disk on the end of the bucket, and Figure 9 is an edge view of the latch-disk showing it attached to the bucket and also showing one of the bucket trunnions rigid with the disk.

Figure 10 is a face view of one of the bail-brackets showing one of the trunnions supported therein, and Figure 11 is a view looking from the right in Figure 10.

Figure 12 is a broken, detail view showing the combined trip-lever and latch, the latter in engagement with a portion of the latch-disk of the bucket.

Figure 13 is a detail edge view of the latch arm, detached from the trip lever or latch lever.

In the first three views where the general assembly and relation of parts are disclosed, two tandem-trolleys or wheeled carriages 1 and 2 are shown rolling on the overhead rail 3, and the rigid hanger frame 4 is suspended from the carriages at swivel points 5, 5. A traction cable 6 is engaged by the grip device 7 on the hanger-frame, and the cable tows the conveyer in the usual manner.

At the lower end of the hanger-frame are arranged two parallel bars 8, 8, forming rigid parts of the frame and extending in a plane parallel with the plane of the overhead rail, but as shown in Figure 2 the hanger frame and its two bars are offset from the plane of the rail.

The two bars are spaced apart and a pivot pin 9 is passed through complementary openings in the bars, said pin having a head 10 at one end and a washer 11 and cotter pin 12 at the other end, the washer and head serving to retain the pin against displacement.

Below the hanger frame the dump bucket 13 is suspended by means of its angularly shaped bail 14, the bail 14 being provided

with a bearing plate 15 bolted to the under-side of the angular bail, and it will be apparent in Figure 4 that the apex of the angular bail and its bearing plate 15 form a pivotal bearing, between the two bars 8, 8 on the pin 9. The bail is thus permitted to swing on the transversely arranged pivot pin, after the latter has been passed through the bearing and is supported in the bars, but the two bars prevent lateral swinging of the bail. While the bucket 13 is held rigid with its bail, as will be described, it will be apparent that the bucket cannot sway or swing laterally, because of the arrangement of the bail and the two bars, and the bucket is therefore held against relative lateral movement by the hanger-frame.

At the lower ends of the bail are provided a pair of open brackets 16, bolted at one side of the bail, and each provided with an opening 17 and a smaller bearing slot 18 at the lowermost end of the bracket.

At the exterior of and on opposite ends of the bucket are mounted circular disks 19 and 20 which are secured to the bucket by bolts 21 passing through holes 22 in the disks and the bolts of course pass through the walls of the bucket. Each disk is fashioned with a trunnion 23 and each trunnion has a head 24, the latter of a size to be passed through the large opening 17 of the bracket, but the head is larger than the bearing slot 18 which receives the trunnion, and the head prevents dislocation or displacement of the trunnion from its bearing slot. As best seen in Figure 2, the bucket is thus pivoted at points offset from the bail, and the bucket is adapted to swing clockwise in Figure 2, to inverted position for dumping its load, after the bucket has been released from its rigid connection with the bail.

At least one of the circular disks, as 19, is provided with a peripheral notch or socket 25 and the periphery of the disk is adapted to turn adjacent the inner side of the bail-bracket. A lever arm or latch-arm 26 is located in the same plane with the disk and adjacent its periphery, and this arm, at its upper end is pivoted at 27 at the inner side of the bracket and adapted to swing with relation to the bracket. At its lower end the arm is fashioned with a head 28 complementary to the socket or notch 25 of the disk into which it is adapted to fit, a guide shoe 29 being secured on one wall of the notch or socket to guide the head, and to hold it against lateral movement. A trip lever 30 is secured in a groove 31 in the face of the latch arm, and is secured rigidly to the arm by bolts or screws 32.

The lever 30 projects in approximately horizontal position a suitable distance beyond the rear side of the bucket, as indicated in Figure 2, and as the bucket travels toward its destination, the lever, in its latched posi-

tion retains the bucket against turning movement on its trunnions.

When the bucket approaches its dumping station the free end of the lever rides up a stationary incline or cam face which causes the lever and its rigid latch arm 26 to swing upwardly on the pivot 27 thereby withdrawing the latch head 28 from its notch or socket 25.

A roller or other contact device, as 33 is mounted on the end of the bucket, as indicated in Figures 2 and 6, above the lever and in its path of movement, and when the lever is lifted to release the latch the former contacts with the roller 33, thereby tilting the bucket to turn clockwise in Figure 2, and the bucket in turn inverted or turned to dumping position by gravity.

The weight of the lever 30 causes the lever-latch to fall, after the lever leaves the cam or incline, and the head 28 of the latch falls against the periphery of the disk 22, and remains in frictional contact with the periphery of the disk. When the bucket is again righted or turned to loading position by suitable means, the socket 25 turns to proper position to permit the head to fall into it, and the bucket is then retained in righted position, or latched, to receive its next load.

The bucket may readily be removed from its suspending bail by first lifting the bucket to free its trunnions from their bearing slots 18, and then the trunnions may be "worked" out through the openings 17, or the bucket and bail may readily be detached from the hanger frame, by first removing the cotter pin 12 and then pulling out the pivot pin 9, if repairs or replacements are necessary.

Having thus fully described my invention, what I claim as new and desire to secure by Letters Patent is:—

In a conveyer bucket, the combination with a suspending frame having a pair of spaced, lower, parallel bars and a transversely extending pin joining said bars, of an angular bail pivoted on the pin and between said bars to prevent lateral sway of the bail, a complementary bearing plate beneath the pin and bolted to the angular bail, brackets on the ends of said bail, offset bearings on said brackets, a tiltable bucket journaled in said brackets, co-acting means on said bucket and one of the brackets for latching the bucket, and means for releasing the latching means.

In testimony whereof I affix my signature.

ROYAL N. RIBLET.
